UNITED STATES PATENT OFFICE.

ADOLPH G. HOELSCHER, OF BOSTON, MASSACHUSETTS, ASSIGNOR TO
ALFRED T. PALMER, OF BOSTON, MASSACHUSETTS.

BOOKBINDING.

SPECIFICATION forming part of Letters Patent No. 751,431, dated February 2, 1904.

Application filed September 3, 1903. Serial No. 171,721. (No model.)

To all whom it may concern:

Be it known that I, ADOLPH G. HOELSCHER, of Boston, in the county of Suffolk and State of Massachusetts, have invented certain new and useful Improvements in Bookbinding, of which the following is a specification.

The object of my invention is to produce an exceptionally strong and durable binding by making the two covers coöperative and mutually interdependent, so that the book-back is reinforced and any strain on either cover is partially borne and resisted by the other through the peculiar arrangement of the lining material.

In the drawings, Figure 1 is a perspective view of a book embodying my invention complete except for the fastening of one of the end sheets to its cover, shown partly broken away. Fig. 2 is a partial end view with the cover removed, showing one method of inserting lining-strips. Fig. 3 is a partial perspective before applying the cover, showing the method of disposing said lining-strips.

The method of operation is as follows: Between the back edges of the two outer "signatures" (so called) 5 6 and their respective adjacent ones 7 8 I insert the fold of two unequally-folded pieces of linen duck or other suitable lining material 9 10, having their projecting

flaps or ends 11 12 of shorter length than the projecting flaps or ends 13 14. (See Fig. 2.) These folded pieces 9 10 may be and preferably are first fastened to their adjacent signatures 5 7 and 6 8 by means of sewing or gluing, or the

fastening may be part of the one operation of sewing the entire book-forming material which unites all the signatures. In the preferred method the four outer signatures 5 6 7 8, with their inserted folds 9 10, after being

fastened as described are placed in proper juxtaposition to the rest of the book-forming material E (see Fig. 2) and the whole sewed through the two folds in any suitable manner. I next place the front and back end leaves 15 16 in position and with a proper adhesive secure to them the short flaps or projecting ends

11 12 of said folded pieces 9 10, as shown in Figs. 1 and 3. I then slit the projecting ends 13 14 of the folded pieces 9 10 each into sev-

eral strips, preferably three, as 18 20 22, with the middle one about as wide as the other two, and applying a coating of adhesive substance to the back of the book-forming material E I fasten strips 18 21 22 to said back, thus giving it one complete covering of the lining material, the narrow strips 18 and 22 belonging to fold 9 and the wider strip 21 to fold 10. The extra lengths of the strips 18 21 22 in excess of the width of the book-forming material E are then cut off, as shown at C, Figs. 1 and 3, preliminary to forming the double back. A coating of the adhesive mixture is then applied hot to the outside of said strips 18 21 22, and strips 19 20 23 are then fastened over them, making a second complete back covering formed from the lining material. The free ends or extra lengths of these latter strips 19 20 23 integral with the opposite lining-pieces are not cut off, but are fastened, with the end leaves 15 16, to the covers, ends 19^a and 23^a to cover A and end 20^a to cover B, thus reinforcing the hinge-joints formed by the flaps 11 12.

To give greater strength, the back portion D of the cover can be fastened to the book-lining and the book-forming material by the use of proper adhesives.

It is understood that in case the book-forming material is made up of separate sheets the folded pieces 9 10 would be inserted several sheets from the outer ones.

Having thus described my invention, what I claim is—

1. In the binding of suitable material into book form, the described combination and arrangement of the book-forming material, the lining material, and the covers, the folded edge of each lining-piece being secured between an outer signature and one adjacent thereto, and its flaps extended thence in opposite directions, and respectively secured to the opposite covers, whereby said covers are effectively supported and made mutually interdependent through the reinforcing agency of the lining material, substantially as set forth.

2. The described improvement in binding embodying assembled sections or signatures and folded lining-pieces interposed along the

fold between the two outer signatures and those intermediate, all permanently united by the transverse stitching of the book-back, and combined with the external cover, one flap of 5 each lining-piece extending from its fold and seam and fastened to the adjacent cover, while the other flaps of said pieces extend directly across the book-back, overlapping and adhering to each other the outermost one being fastened terminally to the opposite cover, substantially as set forth.

3. The described improvement in binding books, embodying assembled sections or signatures and folded lining-pieces secured along 15 the fold to the two outer signatures, and all permanently united by the transverse stitching of the book-back, and combined with a

suitable cover, the outermost flap of each lining-piece being secured to the inner face of the adjacent cover, and the innermost flaps of 20 such pieces being formed into parallel strips, extended alternately from opposite directions across the book-back, fastened thereto and to each other in superposed position, and the terminal portion of each outside strip, when so 25 superposed and united, being fastened to the inner face of the opposite cover, substantially as set forth.

In testimony whereof I have affixed my signature in presence of two witnesses.

ADOLPH G. HOELSCHER.
